UNITED STATES PATENT OFFICE

168,396

TRUNDLE TOY

Ralph W. Crawford, East Aurora, N. Y., assignor
to Fisher-Price Toys, Inc., East Aurora, N. Y.

Application June 24, 1952, Serial No. 20,337

Term of patent 14 years

(Cl. D34—15)

To all whom it may concern:

Be it known that I, Ralph W. Crawford, a citizen of the United States, residing at 512 Ridge Avenue, East Aurora, in the county of Erie and State of New York, have invented a new, original, and ornamental Design for a Trundle Toy, of which the following is a specification, reference being had to the accompanying drawing, forming part thereof.

Fig. 1 is a side elevational view of a trundle toy showing my design;

Fig. 2 is a top plan view thereof;

Fig. 3 is a front end elevational view thereof; and

Fig. 4 is a rear end elevational view thereof.

The side of the toy not shown in Fig. 1 is identical with the side shown therein.

I claim:

The ornamental design for a trundle toy, as shown and described.

RALPH W. CRAWFORD.
